DESIGN FOR A BOTTLE

John Whitlock Wallace, Statesville, N. C., assignor to Cincolade Company, Statesville, N. C., a corporation

Application March 2, 1934, Serial No. 50,913

Term of patent 14 years

To all whom it may concern:

Be it known that I, JOHN WHITLOCK WALLACE, a citizen of the United States, residing at Statesville, in the county of Iredell and State of North Carolina, have invented a new, original, and ornamental Design for Bottles, of which the following is a specification, reference being had to the accompanying drawing, forming part thereof.

Figure 1 illustrates a front perspective view of the bottle embodying my new design; and Figure 2 shows a front elevation thereof.

I claim:

The ornamental design for a bottle, as shown.

JOHN WHITLOCK WALLACE.
